(57) **CLAIM**

The ornamental design for a glove, as shown and described.

DESCRIPTION

FIG. 1 is a front perspective view of the glove. The dashed lines indicate stitching and form a part of the claimed design. FIG. 2 is a back perspective view of the glove. The dashed lines indicate stitching and form a part of the claimed design. FIG. 3 is a front view of the glove. The dashed lines indicate stitching and form a part of the claimed design. FIG. 4 is a back view of the glove. The dashed lines indicate stitching and form a part of the claimed design.

FIG. 5 is a right side view of the glove. The dashed lines indicate stitching and form a part of the claimed design. FIG. 6 is a left side view of the glove. The dashed lines indicate stitching and form a part of the claimed design. FIG. 7 is a top view of the glove. The dashed lines indicate stitching and form a part of the claimed design; and, FIG. 8 is a bottom view of the glove. The dashed lines indicate stitching and form a part of the claimed design. FIGS. 1-8 shows a right hand glove or portions of a right hand glove. The left hand glove and the portions of a left hand glove, which are not depicted in the drawings, are the mirror images of FIGS. 1-8.

The circles shown on the pads on the front side of the glove represent holes that extend through the outer layer of the pads.
